(57) **CLAIM**

The ornamental design for a sound bar, as shown and described.

DESCRIPTION

1.1 is a front view of a sound bar showing a first embodiment of new design;

1.2 is a back view thereof;

1.3 is a left view thereof;

1.4 is a right view thereof;

1.5 is a top view thereof;

1.6 is a bottom view thereof;

1.7 is a front, left side perspective view thereof;

4.1 is a front view of a sound bar showing a second embodiment of new design;

4.2 is a back view thereof;

4.3 is a left view thereof;

4.4 is a right view thereof;

4.5 is a top view thereof;

4.6 is a bottom view thereof;

4.7 is a front, left side perspective view thereof;

5.1 is a front view of a sound bar showing a third embodiment of new design;

5.2 is a back view thereof;

5.3 is a left view thereof;

5.4 is a right view thereof;

5.5 is a top view thereof;

5.6 is a bottom view thereof; and

5.7 is a front, left side perspective view thereof.

(Continued)

The broken lines shown in the drawings illustrate portions of the sound bar that form no part of the claimed design.
